CERAMIC PETAL CUTTING MEANS

Rex E. Gentry, Chesterfield, Ind.

Application February 29, 1952, Serial No. 274,190

3 Claims. (Cl. 25—105)

1

This invention relates to perimetric cutters, that is, cutters corresponding in shape to the perimeters of objects to be cut. More specifically, it relates to cutters for cutting artificial flower petals from rolled-out ceramic "dough" or other plastic material, a number of the cut-outs being further shaped by hand and assembled to form an artificial flower.

An object of the invention is to provide an exceptionally simple and inexpensive cutter which will provide the cut-out petal with an attaching lug at its inner end, whereby these lugs of the various petals may be secured together to hold the various petals assembled. When using a ceramic, for instance, the mere pressing of the lugs together before the material sets will integrally secure the various lugs together.

Another object of the invention is to provide a set of the cutters of different sizes and to so construct said cutters that they may be compactly nested when not in use to reduce the likelihood of one cutter or another being misplaced.

A further object of the invention is to provide a nest of the cutters in which the various cutters are yieldably held in nested relation and may be readily separated for individual use.

A still further object of the invention is to provide a nest of cutters in which the individual cutters are yieldably gripped by each other at one end and at their other ends are provided with interengaging detents and sockets which yieldably hold them in nested relation.

With the above and other objects in view that will become apparent as the nature of the invention is better understood, the same consists in the novel form, combination and arrangement of parts hereinafter more fully described, shown in the accompanying drawing, and claimed.

In the drawing:

Fig. 1 is a side elevation of one of the cutters,
Fig. 2 is an end view,

Fig. 3 is a top plan view showing a set of the cutters of different sizes and in nested relation, and

Fig. 4 is a longitudinal sectional view on line 4—4 of Fig. 3.

A set of four cutters 5, 6, 7, and 8 has been shown. These cutters are duplicates except for size and a description of one will therefore suffice. All of the reference numerals used in describing the cutter construction will be found on the cutter 5 and they will be duplicated only where advisable on the other cutters.

A simple strip of aluminum alloy or other

5 somewhat springy material is used in forming each cutter. Substantially midway between its ends, this strip is bent to form an arcuate end wall 9 of somewhat more than 180° in length. From the ends of this end wall 9, the two end portions of the strip converge into closely spaced relation to provide major side wall portions 10. From the ends 11 of these major side wall portions, the end portions of the strip are extended 10 outwardly in closely spaced substantially parallel relation to form minor side wall portions 12. From the outer ends 13 of these minor side wall portions, the strip end portions are converged together at 14. The two terminals of the strip 15 are secured together by extending them outwardly in contact with each other as shown at 15 and clinching one around the other at 16. The formations 14, 15, and 16 provide a second and smaller end wall opposite the end wall 9 and of substantially Y shape.

The central portion of the end wall 9 is outwardly deformed, providing a rounded projection 17 at the outer side of said wall and a shallow rounded socket 18 in the inner side of said wall.

When the cutters 5, 6, 7, and 8 are nested as seen in Figs. 3 and 4, their arcuate end walls 9 contact yieldably with each other and the various projections 17 and sockets 18 interengage as 30 seen in Fig. 4. The Y-shaped end wall 14a of the cutter 6 is yieldably received between the ends 11 of the converging side wall portions 10 of the outer cutter 5. The side wall portions 12 of the outer cutter 5 yield outwardly as the 35 end wall 14a of the cutter 6 is wedged into place and said portions 12 are thus tensioned to yieldably grip this end of said cutter 6. The shank portion 16a of the Y-shaped end wall 14a of cutter 6 lies between the wall portions 12 of the 40 cutter 5 and the Y-shaped end walls of these two cutters 5 and 6 are free from contact with each other. The cutters 6 and 7 are associated with each other in the same manner, and the same is true of the cutters 7 and 8.

45 The cutters are of such length that each one is tensioned somewhat by the nesting operation. Thus frictional contact at the smaller ends of the cutters coacts with the detents and sockets at the larger ends to firmly hold the cutters nested. During nesting, the springy characteristic of the cutters causes the detents to snap into the sockets and while some force is required to separate the cutters for use, this 50 is not undesirable. On the contrary, it is ad-

vantageous to prevent accidental disconnection of the cutters.

Any selected cutter may be used by simply pressing one or the other of its edges through rolled-out ceramic "dough" or similar material. The material cut by the portions 9 and 10 is then hand-shaped to form an attractive petal, and the material cut by the portions 12 and 14 forms an attaching lug for said petal. By pressing these lugs of various petals firmly together before the "dough" hardens, said lugs become integrally united and hold the petals in their proper relation to provide an attractive artificial flower.

From the foregoing, it will be seen that novel and advantageous provision has been made for attaining the desired ends, and while there is herein shown and described the preferred embodiment of the invention, it is nevertheless to be understood that minor changes may be made therein without departing from the spirit and scope of the invention as claimed.

I claim:

1. A perimetrical cutter for producing ceramic blanks for simulating of roses and the like, said cutters comprising a body of strip type formed of springy metal of uniform width and thickness to provide a cutter having its opposite edges of similar dimensions and contour to permit either edge to serve as the cutting edge, said strip having an intermediate portion of its length shaped into an arcuate curvature for a distance of at least a semi-circular length of 180°, the curved shaping being continued from the ends of such intermediate length with the curvature at a slower rate and approaching a position diametrically opposite the mid-point of the intermediate curvature of the strip length, the positions being spaced apart the distance of the width of the petal stem of the blank, the end areas of the strip being connected with the ends of such curvature length by a first abrupt turn and continued in parallel relation for a distance to provide the length and width of the stem, and then continued with a second abrupt turn for continuation through an inclined length into a contact relation of short length and terminating in a secured end by one strip end extending in overlapped relation to the other end of the strip, the mid-length point of the curvature length having a concavo-convex member projecting outwardly therefrom, the formed blank receiving its manual manipulations at will and prior to subjecting the complete blank to the final ceramic regimen treatment.

2. A nested set of perimetrical cutters including at least two adjacent cutters each being constructed as defined in claim 1, said cutters differing from each other in the contour length dimension of the perimeter of the blank-cutting interior of the cutter to provide a symmetrical relation between the two cutters and of the blanks produced therefrom, the nesting relation of the two cutters presenting a contacting relation at the respective mid-length points in the curvature areas of the two cutters with the remaining contact presented by the contact of the second abrupt

turn of the smaller cutter with the first abrupt turn of the larger cutter, the remaining contour portions of the two cutters being out of contact, the respective contact points placing the two cutters under slight tension with the contacts spaced diametrically of the nested cutters, the end closure of the smaller cutter being received within the blank stem-producing space of the larger cutter and with the stem producing space of the smaller cutter located within the curved contour of the larger cutter, the differences in the symmetrical perimetrical length dimensions being controlled by the differences in length of the blank body and stem portions of the perimetrical contour.

3. A nested set of perimetrical cutters for producing ceramic blanks, said set comprising four cutters each being constructed as defined in claim 1 with the cutters operative actively as individuals and positioned in nested relationship to maintain the integrity of the set and to protect the controlling cutting edges of the individual cutter, said set of cutters being operative to produce the blanks for simulating the individual petals of a partly-open or full-blown rose or like petalled flower, said cutters differing from each other in the length dimension of the contour perimeter of the cutting edge of the blank petal body and its stem, the differences in such edge length dimension being symmetrical to each other in the cutters of the set to individually present the petal body and stem of petals forming a predetermined annular series of petals with the length dimensions of successive cutters of the set corresponding to the successive length dimensions of the individual petals of a predetermined series, the respective shapes of the cutters and their contour perimetrical dimensions limiting the contact of adjacent cutters of the nested set to a limited area in the mid-length of petal body contour and to a contact of the second abrupt turn of the smaller cutter with the first abrupt turn of the larger adjacent cutter with the remaining perimetrical areas of the adjacent cutters free from contact to thereby limit the contacts to diametrically aligned positions remotely spaced to permit slight tension effects therebetween, the cutters producing the blanks individually with all of the cutters individually active in producing the petal blanks for the rose or other product, the assemblage of the blanks into the product being by the uniting of the stems of the blanks after the individual manual facial manipulation of the petal body of the blank and prior to the final ceramic treatment of the assemblage.
